DES. 2112

Henry G. Thompson of New York, N.Y.

Assignor to

The Hartford Carpet Company of Hartford, Ct.

Letters Patent No. 2112, Dated July 4th 1865

Design for a Carpet pattern

The Schedule referred to in these Letters Patent and making part of the same.

To all whom it may concern

Be it known that of Henry G.

Thompson of the City, County and State of New York,
have invented or produced a new and original Design
for a Pattern to be wrought into two ply Tigraine
and other Carpeting, in colors similar to those painted
on the drawings accompanying this Specification, or
in other colors substituted in the place of those painted
on the drawings herewith; and I do hereby declare that
the drawings accompanying this Specification do give
and convey to any one skilled in the Art of Carpet weaving
a more defined and thorough description of the nature
of my invention than it is in the power of language
otherwise to convey, and is sufficient to enable any one
skilled in the art of Carpet weaving to use my invention.

What I claim as my invention and desire to secure
by Letters Patent, is the configuration of the Design herein
annexed, when made by being wrought into two
ply Tigraine or other Carpeting, in the form similar
to the drawings accompanying this Specification.
